PRESSURE CASTING MACHINE

Benjamin L. Levinson, Great Neck, N. Y., assignor, by mesne assignments, to Solar Aircraft Company, San Diego, Calif., a corporation of California

Application February 21, 1944, Serial No. 523,234

1 Claim. (Cl. 22—57)

1 This invention relates to a pressure casting machine for making dense metal castings.

The prime object of my present invention centers about the making of castings of metals and metal alloys possessing to a high degree soundness, strength and shape accuracy. This prime object is accomplished by the provision of the improved pressure casting machine of the present invention, embodying a construction, at once simple in design, which enables the carrying out of those steps of the casting operation which produce metal castings possessing these described characteristics.

A further prime object of the invention is the provision of an improved pressure casting machine which may be operated rapidly and efficiently, so that the desired castings may be made on a high production basis and with repeated uniformity.

The pressure casting machine of the present invention lends itself efficiently to the making of castings, particularly of moderately large size, having uniform denseness and shape accuracy. The produced castings possess both a highly uniform body denseness or body soundness and an accuracy of form or shape, combining also therewith a finished surface or skin, the combination of which reduces and in fact eliminates the need of any subsequent surface machining. Such castings are also found to possess unusual tensile and compression strengths.

The pressure casting machine of the present invention may be used for any type of mold and is here exemplified for use with a flask mold. The flask mold is removably mountable in the casting machine for the casting operation. In this type of machine, where the casting is small in size or/and simple in shape, the metal is either melted directly in the flask or poured into the flask in a molten condition, after which the flask is sealed and the melt placed under pressure for compression filling of the flask mold cavity. While this type of machine has in prior practice served effectively for small or simple shaped castings, difficulties arise where the casting is of generally large proportions or/and embodies a complex shape. Then the step sequence of the method and the timing of the steps play important roles in the procedure or technique. Moreover, the timing of the steps depends upon and consequently must be varied with the nature of the metal being cast. The casting machine must, therefore, be properly organized to permit these operations and also such varying or flexibility thereof. The provision of an improved pressure

2 casting machine of this type, capable of such operation and use, is the prime desideratum of the present invention.

To the accomplishment of these objects and such other objects as may hereinafter appear, the invention relates more particularly to the pressure casting machine sought to be defined in the appended claim and disclosed in the accompanying specification in connection with the appended drawings in which:

Fig. 1 is an elevational view of the pressure casting machine of the present invention, with parts shown in section;

Fig. 2 is a side view thereof taken in cross-section in the plane of the line 2—2 of Fig. 1;

Fig. 3 is a view of Fig. 1 taken in cross-section in the plane of the line 3—3; and

Fig. 4 is a sectional fragmentary view of a modification thereof.

Referring now more in detail to the drawings and having reference first to Figs. 1 to 3 thereof, the casting machine is intended to be used with molds such as the mold M of the flask type. The mold M is of the investment type consisting of a metal flask 10 containing a refractory investment material 12 which has a mold cavity 14 produced therein by the "lost wax" method, the said mold cavity having branches 16 and 18 communicating with the sprue opening 20. The sprue opening 20 preferably terminates in a funnel shaped end 22 at the pouring end or face of the flask. The flask 10 preferably comprises a tubular element open both at its bottom 24 and at its top 26.

The flask mold M is removably receivable by the pressure casting machine for a pouring operation. The pressure casting machine generally designated as C comprises a support for receiving and sealing the mold flask M, said support comprising a stand 28, a seat 30 for the flask bottom 24 vertically movable in the stand 28, and a head 32 for the flask top 26 preferably fixed to the stand 28. By the movement of the seat 30, the mold flask M is received in the casting machine and sealed for a pouring operation and is withdrawn from the casting machine after the metal poured therein has been pressure filled and solidified.

It is important, particularly in making a large sized or complex casting having the desired denseness and soundness throughout coupled with the desired shape accuracy and skin finish, to properly carry out the operational sequence of steps and to correctly time the same with such variance in timing introduced which is depend-

ent upon the nature of the metal being cast. It is, therefore, desirable to coordinate such factors as the preconditioned temperature of the mold flask M, the nature of the pouring channel or duct, the pressure employed for compression filling of the mold cavity, and the time lapse between the pouring step and the step of application of the pressure. Moreover, the operational steps involved should desirably be of such a simple character and carried out with such simple equipment that the operator be afforded a sufficient margin of latitude for timely carrying out the different steps of the technique and for varying the timing dependent upon the nature of the metal being cast.

In the practice of the method, the mold flask M is placed in a suitable furnace and heated to elevated temperatures. The particular temperatures to which the flask is heated depends largely upon the melting point of the metal or alloy to be cast. Taking, for example, a high melting point metal or alloy such as stainless steel having a melting point around 3000° F., the mold M is heated to temperatures generally approaching this melting point, such, for example, as 1600° F. Taking as another example an alloy in the low melting point range, such, for example, as a magnesium alloy, having, say, a melting point of 1100° F., the mold is heated in the furnace to a temperature of from 500° to 750° F. While the mold is being heated, the metal to be cast is brought up to its melting point in a suitable retort or furnace. The mold M thus preconditioned is placed into the casing machine C and sealed in position between an asbestos liner 34 in the seat 30 and the asbestos liner 36 in the head 32. In this position as shown in Figs. 1 and 2 of the drawings, the mold is ready for a casting operation.

To carry out the objects of the invention, the melted metal is poured by means of a suitable ladle through the head 32 and into the mold cavity of the flask M. To this end the head 32 is provided with a pouring duct 38 which communicates directly with the sprue opening 20 of the mold cavity, the diameter of this pouring duct being preferably of increased size, comparable, for example, to the diameter of the top of the funnel shaped part 22 of the sprue opening. The top of the head 32 is formed with an opening 40 for receiving a funnel member F shown in Fig. 4 of the drawings, the discharge end 42 of which is of a diameter substantially smaller than the diameter of the pouring duct 38. The funnel F which may be made of a graphite material is removably receivable by the head 32 and is also preheated to temperatures comparable to the preconditioned temperatures of the mold M. The described diameters for the pouring duct 38 and the funnel F are such that when the metal is ladled into the funnel and gravitationally flows therefrom into the flask, the metal will not contact the walls of the pouring duct 38 thereby avoiding any chilling thereof. By means of this construction, therefore, the metal is poured into the mold by way of the casting machine head 32 and through the pouring duct 38 thereof.

After this pouring operation, pressure is ready to be applied to the metal in the mold for compression filling of the mold cavity. It is important to correctly determine within limits the time lapse between the pouring of the metal and the application of the pressure. This time lapse is comparatively short in any event but may vary within substantially wide limits. Thus, for ex-

ample, with a high melting point metal such as steel, this time lapse may be as short as $\frac{1}{2}$ of a second, while with a low melting point such as aluminum, this time lapse may be as much as 5 seconds. After the pouring operation, the apparatus provided is in a condition to have the pressure applied either immediately, such as within the fraction of a second, or within the period of a few seconds. To accomplish this, the head 32 is provided with means preferably in the form of a valve for opening the pouring duct 38 for a metal pouring operation and for closing and sealing said duct after such a pouring operation, and is also provided with means for connecting a gas pressure supply to the charging duct and particularly the mold cavity for placing the same under the desired pressure when the duct has been closed and sealed. To accomplish these ends, the head 32 is provided with a valve 44 resiliently seated in a valve seat 46 formed in said head and operable by means of a handle 48 fixed to the valve stem. The valve is resiliently urged into the head by means of a spring 50 which is anchored against a threaded valve holding nipple 52 adjustably mounted in the head. The valve has a port 54 which registers with the pouring duct 38 for opening the same when the valve is moved to the position shown in Figs. 1 and 2 and for closing the same when the valve is moved to a position 90° therefrom. In the position shown in Figs. 1 and 2, the pouring duct 38 is open for a pouring operation, and when the valve is moved to the 90° position, the duct is closed and the mold cavity is sealed.

For connecting the mold cavity to a gas pressure supply, the head 32 is provided with the ports 56 and 58, the port 56 communicating with a pipe 60 leading to a gas pressure supply and the port 58 opening into the pouring duct 38 at a position below the valve 44. In the form of the invention shown in Figs. 1 and 2, the gas (air) pressure is applied automatically when the valve is moved to the 90° position to seal the mold, and to this end the valve 44 is provided with a port 62 which functions to close the supply of pressure from the pipe 60 when the valve 44 is in the metal pouring position, and which functions to open the mold cavity to the pressure supply when the valve is moved to the 90° position to close and seal the pouring duct. It will be understood that the operator, after ladling the metal through the pouring head, will wait the selected time (from a fraction of a second to several seconds) before he operates the valve 44, and that upon operation of this valve, sealing of the flask will take place with the concomitant application of the air pressure. The degree of air pressure employed depends upon the type of metal being cast. This will vary from 10 pounds for some metals to 35 to 50 pounds per square inch for metals such as steel.

The stand 28 may suitably comprise a base plate 64 to which is anchored the supporting posts 66 and 68. The seat 30 is mounted to move vertically in said posts and the head 32 is fixed to the top of the posts as shown, also thereby serving in conjunction with the bottom plate 64 to produce a rigid stand frame. For moving the seat 30 (for removably mounting and sealing the flask M) I preferably provide the mechanism best shown in Figs. 1 and 2 of the drawings, which comprises a central post 70 externally threaded as shown for vertical adjustment in the correspondingly threaded base plate 64, the post being held in any adjusted position by means of the lock screw 72.

The post 70 seats at its top a cam holder 74 which is rotatably adjustable in the post and which may be held in any adjusted position by means of the lock screw 76. In the holder 74 is mounted a cam 78 operated by means of a handle 80. The cam engages a spring member 82 which is bifurcated at its opposite ends 84 and 86 for reception of the posts 66 and 68 and the body of which resiliently engages the movable seat 30. By means of this construction the seat may be elevated (resiliently) by moving the cam 78 to the position shown in Figs. 1 and 2 of the drawings and may be lowered (for permitting reception or removal of the flask) by a 180° movement of the cam. The post 70 is adjustable to accommodate different sizes or heights of flasks, and the cam holder 74 is adjustably rotatable in the post so that no matter to what position the post is rotated, the cam 78 may be moved to its correctly aligned position as shown in Figs. 1 and 2 of the drawings.

In the modification shown in Fig. 4 of the drawings, a different form of valve is used in the head of the casting machine and this valve is not directly connected with the pressure supply. Otherwise the construction as shown in Fig. 4 is the same as that shown in Figs. 1 to 3 and the parts thereof are designated by the same but primed reference characters. In this modification the valve comprises a gate or slide valve 88 movable by means of a handle 90, and the pressure supply source is connected directly from the pipe 60' through a manually operable valve 92 to a port 84 leading into the pouring duct 38' at a point below the seat of the gate valve 88.

The construction and operation of the pressure casting machine of the present invention and the described advantages thereof will in the main be fully apparent from the above detailed description thereof. The casting machine presents a very simplified piece of equipment. A large number of these may be arranged in gang formation to be operated or used sequentially by one operator. The mold or flask for each machine after being preheated is quickly placed and sealed into the casting machine by the operation of the cam handle 80. The operator then ladles his metal into the mold through the preheated flask F and the head of the casting machine; and the structure and operation of the machine are so simplified that the operator may carry out a series of pouring operations for sequentially positioned casting machines. With the timing selected according to the character of metal being cast, the operator may then close the valve in the casting

machine head and open the mold, manually or automatically, to pressure. When the resulting casting is solidified, the flask is removed and the casting detached therefrom. The castings obtained possess the described soundness, strength, shape accuracy and surface finish.

While I have exemplified the invention by reference to the use of the casting machine with flask molds, it will be understood that other molds could and are intended to be used therewith, such as sand molds, permanent molds or plastic molds. While I have shown and described preferred embodiments of the casting machine of the invention, it will be understood that changes may be made therein without departing from the spirit of the invention as defined in the following claim.

I claim:

A pressure casting machine comprising a support for receiving and sealing a mold, said support including a stand, a seat for the mold bottom movable vertically in said stand, and a head for the mold top fixed to said stand, means for moving said seat for removably receiving said mold, the means for moving said seat comprising a threaded post vertically adjustable in said stand, a cam holder rotatably adjustable in said post, an operating cam in said holder, a spring member between said seat and said cam and means for operating the cam.
